UNITED STATES PATENT OFFICE

LOUIS H. MESKER, OF SHAKER HEIGHTS, AND JACOB JENNE, OF CLEVELAND, OHIO,
ASSIGNORS TO THE CLEVELAND PLANER COMPANY, OF CLEVELAND, OHIO, A
CORPORATION OF OHIO

KNEE CLAMP FOR PLANERS

Application filed June 11, 1928. Serial No. 284,518.

This invention relates generally to an open side planer and more particularly to a knee clamp for clamping the knee of the planer in the desired position.

5 The main object of the invention is to provide a simple and efficient mechanism for rigidly and firmly securing the knee in the desired position with respect to the column.

Another object of the invention is to provide 10 a simple and efficient knee clamping mechanism by means of which the knee may be securely fastened in the desired position by a single turn of the operating lever.

A still further object of the invention is to 15 provide an improved knee clamp of the character described which is simple in construction, dependable and accurate in operation and well adapted for production at comparatively low cost.

20 Further and more limited objects of the invention will appear as the description proceeds and by reference to the accompanying drawings in which Fig. 1 is a view in front elevation of an open side plane disclosing the 25 relative arrangement of parts; Fig. 2 is a detail fragmentary top plan view illustrating the operating mechanism for securing the knee to the column with parts broken away to show details of the construction; Fig. 3 is a

30 fragmentary vertical sectional view disclosing the means for operating the locking mechanism; Fig. 4 is a fragmentary horizontal sectional view of the left hand end of the column and knee, as viewed in Fig. 2, and Fig. 35 5 is a detail perspective view of the floating gib for securing the parts in position.

All planers of this general type embody a base portion or bed from which rises a column. Mounted for reciprocatory movement 40 on the bed is a table on which the work is supported. Mounted on the column at right angles thereto, and adapted for reciprocatory movement thereon in a vertical plane, is the knee on which is mounted the rail. The rail 45 carries the cutting tools which are mounted directly thereon and adapted for adjustment in both a vertical and a horizontal plane. The knee is a large triangular member which is slidably mounted on the column and adapted to be moved up and down on the column

by means of suitable mechanism well known to those skilled in the art. Due to the size, weight and shape of the knee, great difficulty has been experienced in the mechanism for securely locking the knee in the adjusted position and it is toward this feature that this invention is particularly directed.

55 Referring now to the drawings, the reference character 1 designates the base or bed of the planer on which is mounted the table 2 which is adapted for reciprocatory movement thereon in a vertical plane. Rising from the base member or bed 1 is the column 3 which is disposed at right angles to the bed. Mounted on the column 3 and at right angles thereto is the knee 4 which is adapted for movement in a vertical plane by means of a screw 5 in a manner well known to those skilled in the art. The bearing surfaces on the column 3 project outwardly slightly as 60 shown at 6 and 7, and the central portion of the column is cut away slightly as shown. That portion of the knee 4 embracing the column is shaped as shown most clearly in Fig. 2 so as to engage both the front and back of 65 the column.

70 The left hand edge of the column, as viewed in Fig. 2 is cut at an angle of 15 degrees with respect to the front face 6, as shown at *a* in Fig. 2. The opposite side of 75 the column 3 is provided with a projecting portion 8 the front and side faces of which are at right angles to each other. The rear face of the projection is cut on an angle of 7½ degrees with respect to the side face 80 thereof as shown at *b* in Fig. 2. The knee 4 has a portion 9 which bears against the side face of the projection 8 and a portion 10 which extends beyond and to the rear of the projection 8. The front face of the portion or 85 projection 10 is cut on an angle of 7½ degrees, as shown at *c* in Fig. 2, and normally extends parallel with the surface *b*. Disposed between the surfaces *b* and *c* is a gib or wedge 11 which is of such a size and shape 90 as to just fit therebetween, the purpose of which will hereinafter appear.

95 The opposite end of the knee 4 is also provided with a portion 12 extending beyond the side face of the column and a portion 13 100

extending along and abutting the rear face thereof. By reference to Fig. 4 it will be seen that the portion 12 is spaced a slight distance from the side face α of the column so as to provide a space 14 therebetween.

5   Mounted on the top of the knee 4 is a block 15 having a bore 16 therethrough. Extending through the bore 16 and having a bearing therein is a shaft 17 to the upper end of which is non-rotatably secured a worm gear 18. The shaft 17 projects downwardly through the space 14. The upper portion of shaft 17 is provided with a right hand thread 19 and the lower portion of shaft 17 is provided with a left hand thread 20.

15   Threadedly secured over the upper portion of the shaft is a tapered wedge or block 21 and threadedly secured over the lower portion of the shaft 17 is a tapered wedge or block 22 the taper of which is in the opposite direction from that of sleeve 21. Also arranged within the space 14 is a floating gib 23 one face of which is angular so as to bear against the surface α and the opposite face of which is tapered in opposite direction so as to conform to and bear against the tapered surfaces of the wedges 21 and 22, the purpose of which will hereinafter appear.

30   Carried by the knee 4 and having bearings at the opposite ends thereof is a shaft 24 to one end of which is connected a crank 25. Mounted adjacent the opposite end of the shaft 24 is a worm 26 which meshes with and drives worm gear 18. The worm 26 and worm gear 18 are preferably enclosed within a casing as shown in Figs. 2 and 3. Due to the right and left hand threads 19 and 20 and due to the fact that the blocks or wedges 21 and 22 are held against rotation, it will be seen that when the shaft 17 is turned, the wedges 21 and 22 will be moved toward or away from each other depending upon the direction of rotation of the shaft. It will also be seen that due to the gibs 11 and 23 and due to the angular surfaces α , β and γ , there will be a wedging action in two directions between the knee 4 and the column 3. The difference between the 15 degree angle at the surface α and the $7\frac{1}{2}$ degree angle at the surfaces β and γ causes the gib 23 to move sideways and hold the knee tight against the face of the column.

45   It will now be clear that we have provided a very simple and efficient mechanism for locking the knee to the column. Various changes may be made in the details of construction as well as in the shape of the several parts without departing from the spirit 60 of our invention and we wish our invention to be limited only in accordance with the scope of the appended claim.

Having thus described our invention, what we claim is:

65   The combination with the column and knee

of a planer, of locking mechanism carried by said knee for locking the same in adjusted position, said knee embracing the front and rear sides of said column, the said column having angular bearing surfaces at the front and rear thereof which surfaces are disposed at different angles with respect to the column, gibs interposed between the bearing surfaces of the knee and column and a pair of wedges disposed adjacent one of said gibs and a mechanism for simultaneously moving said wedges in opposite directions, said angular surfaces being so disposed as to cause a wedging action between said knee and column in two directions.

In testimony whereof, we hereunto affix our signatures.

LOUIS H. MESKER.
JACOB JENNE.
